UNITED STATES PATENT OFFICE.

MAURICE FAUQUET, OF PONT-AUDEMER, FRANCE.

CENTRIFUGAL MACHINE FOR THE MANUFACTURE OF FOUNDRY-CORES.

1,099,740.

Specification of Letters Patent.

Patented June 9, 1914.

Application filed January 12, 1914. Serial No. 811,740.

To all whom it may concern:

Be it known that I, MAURICE FAUQUET, a citizen of the French Republic, and resident of Pont-Audemer, France, have invented a new and useful Centrifugal Machine for the Manufacture of Foundry-Cores, which is fully set forth in the following specification.

This invention relates to a machine employing centrifugal force, in the manufacture of molding cores, for introducing the sand into, and for distributing and compressing it in, the boxes arranged in a circle on a mount which carries them around its center in a rapid movement of rotation.

In order to make the following explanations as clear as possible, the accompanying drawings represent by way of example the centrifugal machine for the manufacture of cores according to this invention.

Figure 1 is an elevation of the machine in which the rotating element which forms the main feature of the invention, and the feeding apparatus for the sand, are shown in section. Fig. 2 is a horizontal cross-section on line I—I of Fig. 1, showing the arrangement of the boxes on the rotating element. Fig. 3 is a fragmental view similar to Fig. 1, but showing the position of parts at the moment of the opening of the boxes. Figs. 4 to 6 relate to a modified construction of the machine. In this construction which also has a vertical axis, the rotating parts are driven from below. The same figures show at the same time a modified means for closing the rotating element. Fig. 4 is an elevation, with the rotating element in section. Fig. 5 is a plan view of Fig. 4 and Fig. 6 is an enlarged section on line 2—2, Fig. 5, showing details of a closing bolt. Figs. 7 and 8 relate to another modified construction of the machine. In this construction the axis is horizontal. Fig. 7 is an elevation with the rotating elements in section, the machine being in motion. Fig. 8 is an elevation, the machine being stopped and shown during the opening of the boxes.

The machine in question comprises a cast iron frame A (Fig. 1) provided at the top with a bearing B in which rotates a hollow spindle C through the interior of which the sand is admitted. At the lower end of the spindle C is screwed and secured by a pin a disk D below which is secured a ring a provided on its lower surface with one of

the two mating series of recesses that unite to form the mold cavities c constituting the core-boxes, these cavities opening toward the center of the apparatus to permit them to receive sand. The remainder of the rotating element is constituted by a lower disk E on which is placed another ring b provided at its upper surface with the series of recesses complementary to those of the ring a. The rings a and b are accurately jointed, so as to avoid any leakage of sand. Recesses d and projections e (Fig. 2) arranged specially on the joint plane of the said rings, insure perfect coincidence of the core-box parts comprised in each of them. The upper disk D and the lower disk E are secured together by means of bolts f carried by the former near its edge and held by springs g in closed position. The use of such bolts is not absolutely essential, and there will be subsequently described another closing arrangement which, like the preceding one, must be considered merely as an example. The disks D and E are provided near the center, one with a concave surface, and the other with a convex surface, between which is left a space or chamber F intended to receive sand on its admission into the apparatus. The central convex part of the lower disk E is arranged so that, as soon as the sand arrives, it moves away from the center simply by the action of gravity.

The chamber F is separated from the impression rings a and b by a toothed ring G secured to the lower disk E and provided with openings h widened toward the center of the apparatus, in order to assist penetration of sand into the impressions, to the inlet of which the said openings correspond exactly. The ring G is chiefly intended to cut the sand at the inlet to the boxes after the ramming of the cores, by a slight rotation of the bottom disk relatively to the various other parts constituting the rotating element. Under the lower disk E, in its center, is secured a vibrator J intended to shake the sand during the opening of the boxes. The parts of the rotating element are preferably of aluminium or of other light metal or alloy. The lower part of the frame is provided with two guide bearings H and I through which passes freely a cylindrical rod K vertically adjustable under the action of a system of levers L. To the upper end of the rod K is secured a flanged cup M which when it rises opens the bolts f and re-

ceives the lower disk E carrying the ring b. The receiving cup M is provided at diametrically-opposite points with two angle parts i which prevent its rotation about its axis, 5 as they engage ribs on the uprights of the frame. These two angle parts i must penetrate into recesses or notches made for the purpose in the rib k which projects below the disk E, in order to prevent the rotation 10 of the latter during the cutting down of the cores and the opening of the boxes. At the upper part of the machine, the hollow spindle C carries fast and loose pulleys N and O, and also a funnel P which rotates with 15 the spindle and terminates in a collar l intended to prevent the sand from being scattered during the working. At the extreme top of the machine is arranged a stationary apparatus Q intended to feed sand. It consists of an upper tank m of preferably 20 conical shape, and a paddle wheel n rotatable about a horizontal axis in a case o with which it forms a tight joint, thus insuring a perfect feed of sand. The depending 25 throat p on said case opens into the funnel P.

The foregoing relates however only to one construction of the machine. It is obvious that the invention comprises also any other constructions comprising the rotating element described, whether the latter rotate in a horizontal plane or in a vertical plane, whatever be the method of securing together the disks or the said element, whatever be the drive of the element and whatever be the 30 method of opening of the boxes. The invention is therefore capable of being carried out in numerous ways.

Figs. 4 and 5 show a type of machine which differs from the type shown in Fig. 1 40 first, in that it is driven from below, and, secondly, in that the opening of the boxes is effected by raising the upper disk D and its ring a. This rising movement is produced by an admission of air or water under 45 pressure below a piston R (Fig. 4) which, in rising, lifts a shouldered ring T by means of a pair of vertical rods q which are connected to a cross-head S affixed to the piston, said rods being slidably engaged with suitable guides r and s'. Two vibrators t are 50 made integral with the ring T. Moreover, the tightening of the two disks D and E, against each other, is insured by means of hooks u (Figs. 4 to 6) secured to the bottom disk E and passing through the upper disk D. Under the said hooks engage independent bolts v' pivoted to pins x and held in the closing position by springs y. Simultaneous opening of the bolts is effected by imparting a slight clockwise rotary movement 55 to a ring U which rests upon said bolts and is arranged concentrically with said disks, this ring being formed with slots w' through which project upstanding studs z fixed to 60 the bolts. The said ring is held in one or

the other of its two positions, corresponding to the open or closed positions of the bolts v', by means of a bolt V which alternately engages one or the other of the stops arranged for that purpose on the upper disk. 70

Figs. 7 and 8 show, also by way of example, another construction of the machine. In this construction, the rotating element constituted by the disks D and E and their rings a and b is movable in a vertical plane 75 around the horizontal axis X'-X', (Fig. 7). This element, which is balanced by a weight Z and provided with the pulley N secured to its driving spindle, is designed to oscillate, when the machine is stopped, 80 about a spindle Y carried by the frame A, and then to assume the position shown in Fig. 8, in which the opening of the boxes is effected, for instance, in the same manner and by the same means as those indicated 85 for one or the other of the machines hereinbefore described. The introduction of sand takes place by means of a movable tube W. This type of machine comprises any constructions in which the boxes arranged side 90 by side in any number, have a movement of rotation about a horizontal axis. 95

Claims.

1. In a centrifugal machine for making molding cores, the combination with a driving shaft, of a disk mounted thereon, a movable disk adapted to be fixed to or removed from said disk, said two disks forming a chamber between them adapted to receive sand, coöperating rings on the adjacent face 100 of said disks adapted to form a series of radial core boxes opening into said chamber, and a toothed valve-like ring adapted to make and break communication between the chamber and the core boxes, and to sever the sand at the inner ends of the cores. 105

2. In a centrifugal machine for making molding cores, the combination with a driving shaft, of a disk mounted thereon, a movable disk adapted to be fixed to or removed 110 from said disk, said two disks forming a chamber between them adapted to receive sand, coöperating rings on the adjacent faces of said disks adapted to form a series of radial core boxes opening into said chamber, 115 means for connecting the said disks together, means for removing the movable disk and, a toothed valve-like ring adapted to make and break communication between the chamber and the core boxes, and to sever the sand 120 at the inner ends of the cores.

3. In a centrifugal machine for making molding cores, the combination with a driving shaft, of a disk mounted thereon, a movable disk adapted to be fixed to or removed from said disk, said two disks forming a chamber between them adapted to receive sand, means for feeding sand to said chamber, coöperating rings on the adjacent faces of said disks adapted to form a series 125 130

of radial core boxes opening into said chamber, and a toothed valve-like ring adapted to make and break communication between the chamber and the core boxes, and to 5 sever the sand at the inner ends of the cores.

4. In a centrifugal machine for making molding cores, the combination with a driving shaft, of a disk mounted thereon, a movable disk adapted to be fixed to or removed 10 from said disk, said two disks forming a chamber between them adapted to receive sand, means for feeding sand to said chamber, coöperating rings on the adjacent faces of said disks adapted to form a series of 15 radial core boxes opening into said chamber, means for connecting the said disks together, means for removing the movable disk, and a toothed valve-like ring adapted to make and break communication between the chamber 20 and the core boxes, and to sever the sand at the inner ends of the cores.

5. In a centrifugal machine for making molding cores, the combination with a hollow driving shaft, of a disk mounted thereon, a movable disk adapted to be fixed to or removed 25 from said disk, said two disks forming a chamber between them adapted to receive sand, means for feeding sand comprising a funnel coaxial with said hollow shaft and a rotary sand-feeding device opening into said funnel, coöperating rings on the adjacent faces of said disks adapted to form a series of radial core boxes opening 30 into said chamber, means for connecting the said disks together, means for removing the movable disk, and a toothed valve-like ring adapted to make and break communication between the chamber and the core boxes, and 35 to sever the sand at the inner ends of the cores.

form a series of radial core boxes opening into said chamber, and a toothed valve-like ring adapted to make and break communication between the chamber and the core boxes, and to sever the sand at the inner ends of 35 the cores.

6. In a centrifugal machine for making molding cores, the combination with a hollow driving shaft, of a disk mounted thereon, a movable disk adapted to be fixed to or removed from said disk, said two disks forming a chamber between them adapted to receive sand, means for feeding sand comprising a funnel coaxial with said hollow shaft and a rotary sand-feeding device opening 40 into said funnel, coöperating rings on the adjacent faces of said disks adapted to form a series of radial core boxes opening 45 into said chamber, means for connecting the said disks together, means for removing the movable disk, and a toothed valve-like ring adapted to make and break communication between the chamber and the core boxes, and 50 to sever the sand at the inner ends of the cores.

In testimony whereof I have signed this specification in the presence of two subscribing witnesses.

MAURICE FAUQUET.
